UNITED STATES PATENT OFFICE.

ARCHIBALD MACKINNON, OF TUCKAHOE, NEW YORK.

MOLD FOR MAKING CORK BOARDS.

1,361,081.

Specification of Letters Patent. Patented Dec. 7, 1920.

Application filed March 15, 1920. Serial No. 365,887.

To all whom it may concern:

Be it known that I, ARCHIBALD MACKINNON, a subject of the King of Great Britain, residing at Tuckahoe, in the county of Westchester and State of New York, have invented certain new and useful Improvements in Molds for Making Cork Boards; and I do declare the following to be a full, clear, and exact description of the invention, such 10 as will enable others skilled in the art to which it appertains to make and use the same.

This invention relates generally to molding apparatus, and more particularly to 15 molds for making cork boards or plates out of granulated cork.

One object of the invention is to provide 20 a mold which is divided into two or more compartments so that two or more boards or plates can be formed in the mold at the same time. The compartments may be of different sizes so that different sized boards or plates may be made at the same time.

The partitions which divide the mold into 25 compartments have passages therethrough or are hollow and have openings registering with openings in the mold casing so that the heated air or gases of the furnace through which the mold is passed in the process of 30 making the boards or plates passes through the partitions and heats the various boards or plates from all sides.

Another object of the invention is to provide 35 a mold of this character having a removable top, bottom and partitions, and supplemental detachable wall members carrying partition guides so that the size and arrangement of the compartments in the mold can be varied.

40 Another object of the invention is to generally improve upon devices of this class by the provision of an extremely simple, strong, durable and inexpensive construction, one which will be efficient and reliable in operation, and well adapted to the purpose for which it is designed.

With these and other objects in view, the invention consists of the novel features of construction, and combination and arrangement of parts as will be hereinafter fully described and claimed.

In the accompanying drawings forming a

part of the specification and in which similar reference characters designate like parts throughout the several views;—

55 Figure 1 is a perspective view of a mold constructed in accordance with this invention, the top and top retaining bars being removed from the mold to illustrate the interior construction of the same.

60 Fig. 2 is a longitudinal sectional view through the mold.

Fig. 3 is a transverse sectional view taken on the line 3—3 of Fig. 2.

Fig. 4 is a perspective view of the casing 65 of the mold, the partitions and bottom being removed.

Fig. 5 is a detail horizontal sectional view taken on the line 5—5 of Fig. 2.

Fig. 6 is a perspective view of one of the 70 partitions.

Fig. 7 is a similar view of a portion of a modified form of partition.

Fig. 8 is a perspective view of the mold illustrating a pair of detachable supplemental end wall plates used in connection with the same.

Fig. 9 is a horizontal sectional view taken on the line 9—9 of Fig. 8.

Fig. 10 is a perspective view of one of the 80 supplemental end wall plates.

Fig. 11 is a similar view of a modification of the supplemental end wall plates.

The improved mold consists of a rectangular casing 1, which may be made of sheet or 85 cast metal, but which is preferably as shown made of cast metal. The casing 1 is open at the top and provided at its bottom with an inwardly extending flange or ledge 2, and if desired, with a transverse bar 3. This 90 flange or ledge 2 and transverse bar 3 forms the support for a removable bottom 4, the latter being provided with a number of longitudinally extending openings 5. The upper and lower edges of the end walls of the 95 casing 1 are enlarged in thickness and the upper edges of all of the walls are provided with horizontal flanges 6. The end walls of the casing have a number of vertically disposed openings 7 therein which as herein- 100 after explained, form guides for the ends of the partitions. The side walls of the casing are provided with spaced openings 8 arranged adjacent their upper edges.

Disposed within the casing 1 and having their ends extending through or fitted in the openings 7 so as to support them are partitions 9 which divide the casing into a number of compartments. These partitions 9 may be constructed in a number of ways, the form illustrated in Figs. 1, 2, 3, 6 and 8 of the drawings being made from strips of sheet metal bent along longitudinal lines intermediate of their longitudinal edges so that they are U-shaped in transverse section. The ends of the partitions 9 are preferably closed by means of blocks 10, the latter serving to maintain the walls of the partitions in their spaced parallel relation. The lower edges of the partitions are left open, while the upper edges of the same are provided with openings 11. Extending longitudinally through the partitions 9 along their upper edges and directly beneath the openings 11 so as to close the same and resting upon notches in the upper ends of the blocks 10 are removable rods 12.

The form of partition illustrated in Fig. 7 of the drawings comprises a pair of spaced walls 13 having formed integrally therewith webs 14 which hold them in their spaced relation. This form of partition is open at both the top and bottom edges.

The numeral 15 designates a top which fits into the casing 1 and rests on the upper edges of the partitions 9. This top 15 is provided with a number of longitudinally extending rows of openings 16. The openings 16 register with the openings 11 in the partitions 9, and the openings 5 in the bottom 4 register with the open lower edges of the latter so that a passage through the partitions is provided. After the top 15 is in place, bars 17 are inserted through the aforesaid openings 8. These bars 17 extend transversely across the casing 1 over the top 15 and hold the latter in place.

As clearly illustrated by Figs. 1, 3, 4 and 5 of the drawings, the casing 1 is constructed so as to receive three partitions which are spaced apart and from the walls of the casing which are parallel to them so as to divide said casing into four equal compartments. If it is desired to divide the casing into more or less compartments supplemental and removable walls 18 are used. These supplemental walls 18 are preferably made from sheet metal and comprise plates which are shaped to conform to the shape of the end walls of the casing and are provided at their upper edges with lateral flanges 19 which hook over the upper edges of the end walls of the casing. The partition guides of the supplemental walls 18 are in the form of parallel flanges 20 which are struck from the plates. In this form of device the partitions 9 are of the proper length so that they will nicely fit between the supplemental walls 18, and the bottom 4 and top 15 have

their openings placed so as to register with the openings at the upper and lower edges of the partitions.

When it is desired to divide the casing into a number of compartments of unequal size, supplemental end walls 21 are used. In these end walls 21 the partition guides are spaced unequal distances from their edges and from themselves.

In using the mold the proper bottom 4 is placed in the casing upon the flange or ledge 2, and the partitions are disposed in place with their ends fitted in the openings 7, or in case the supplemental walls 18 or 21 are used, the partitions 9 are fitted in the guides of the latter. Granulated cork is then placed in the compartments formed by the partitions and compressed by suitable means until the mold is filled to the level of the upper edges of the partitions. The rods 12 are, during these operations, disposed in the partition so that none of the granulated cork will pass through the openings 11. The top 15 is then placed in the casing and forced down until it rests on the partitions. The bars 17 are then passed through the openings 8 so as to hold the top in place. The entire mold containing the granulated cork in the state of compression is then passed into a suitable furnace, the heat from which bakes the cork and causes it to adhere so that boards or plates are formed. The heated air or gases of the furnace pass through the partitions so that the heat is applied to the various sides of the plates or boards being formed in the mold.

From the foregoing description taken in connection with the accompanying drawings, the construction, use and operation of the device will be readily understood.

Various changes in form, proportion, and in the minor details of construction may be resorted to without departing from the spirit of the invention as defined in the claims.

I claim:

1. A mold of the class described comprising a casing having open portions therein, and a partition in said casing dividing the latter into compartments and having a passage therethrough communicating with said open portions.

2. A mold of the class described comprising a casing having openings therein, and a partition in said casing dividing the latter into compartments and having a passage therethrough communicating with said openings.

3. A mold of the class described comprising a casing having openings therein, and a hollow partition in said casing dividing the latter into compartments and having openings therein registering with the openings of said casing.

4. A mold of the class described comprising a casing having top and bottom plates

provided with openings, and a hollow partition in said casing having openings in its upper and lower edges registering with the openings in said top and bottom respectively.

5 5. A mold of the class described comprising a casing having partition receiving guides in opposite walls thereof and having its top and bottom provided with openings, and a hollow partition in said casing 10 with its ends fitted in said guides, the upper and lower edges of said partition having openings therein registering with the openings in said top and bottom respectively.

6. A mold of the class described comprising a casing having vertical openings in opposite walls thereof, a removable top and bottom for said casing having openings therein, and a removable partition in said casing having its ends extended through the 20 openings in said opposite walls thereof, said partition having openings in its edges registering with the openings in said top and bottom.

7. A mold of the class described having guides in opposite walls thereof and openings in its bottom, a removable partition in said casing having openings in its upper and lower edges, the openings in the lower edges of said partition registering with the 30 openings in the bottom of said casing, removable means for closing the openings in the upper edges of said partition, and a removable top for said casing having openings registering with the openings in the upper edges of said partition.

8. A mold of the class described comprising a casing having openings in opposite walls thereof and openings in its bottom, a removable partition disposed in said casing 40 and having its ends fitted in the openings in the walls of the latter, said partition having openings in its upper and lower edges, the openings in the lower edge of the said partition registering with the openings in the bottom of said casing, a removable rod

extending longitudinally through said partition adjacent the openings in the upper edge thereof for closing said openings, and a removable top for said casing having openings therein registering with the openings 50 in the upper edges of said partition.

9. A mold of the class described comprising a casing having vertical openings in opposite walls thereof and having openings in its bottom, a removable hollow partition disposed in said casing and having its ends fitted in the openings in the walls of the latter, said partition being made of a plate of metal bent upon itself on a longitudinally extending line and having its intermediate 55 portion provided with a series of openings, said plate having blocks disposed between its portions to hold the latter in spaced relation, the lower edge of said partition being open and registering with the openings in 60 said bottom, a removable rod extending longitudinally through said partition adjacent the upper edge of the same, said rod resting upon the upper ends of said blocks and closing the openings in the upper edge 65 of said partition, and a removable top disposed in said casing resting upon said partition and having openings therein registering with the openings in the upper edge of the latter.

10. A mold of the class described comprising a casing having openings in its top and bottom, supplemental walls removably disposed with said casing and resting against opposite walls of the latter, parallel flanges 75 struck inwardly from said supplemental walls to form guides, and a removable hollow partition disposed in said casing and having its ends engaged with said guides, said partition having openings in its upper 80 and lower edges registering with the openings in said top and bottom respectively.

In testimony whereof I have hereunto set my hand.

ARCHIBALD MACKINNON.
